UNITED STATES PATENT OFFICE.

HERMAN H. PATRY AND LOUIS SAMUEL HANSON, OF CLOQUET,
MINNESOTA.

WATCHCASE.

SPECIFICATION forming part of Letters Patent No. 760,558, dated May 24, 1904.

Application filed April 28, 1903. Serial No. 154,710. (No model.)

To all whom it may concern:

Be it known that we, HERMAN H. PATRY and LOUIS SAMUEL HANSON, citizens of the United States, residing at Cloquet, in the county of Carlton and State of Minnesota, have invented certain new and useful Improvements in Watchcase Construction, of which the following is a specification.

This invention provides a watchcase of the hunting type capable of being manufactured at a reduced cost and involving a less number of parts, the inside back cover and two hinges being dispensed with, and which will be dust-proof and have the case-lift and catch-springs located exterior to the band and in the space formed between it and the case.

For a full description of the invention and the merits thereof and also to acquire a knowledge of the details of construction of the means for effecting the result reference is to be had to the following description and drawings hereto attached.

While the essential and characteristic features of the invention are susceptible of modification, still the preferred embodiment of the invention is illustrated in the accompanying drawings, in which—

Figure 1 is a front view of a watch embodying the invention, the front cover being open. Fig. 2 is a side view, the front cover being open and the back and bezel detached. Fig. 3 is a central transverse section of the case on a larger scale, the movement and front cover being omitted. Fig. 4 is a perspective view of the band. Fig. 5 is a central transverse section of the band. Fig. 6 is a section of the case about on the line X X of Fig. 3 looking to the left, showing the position of the lift and catch springs. Fig. 7 is a perspective view of the catch-spring. Fig. 8 is a perspective view of the lift-spring. Fig. 9 is side view of the band and bezel, showing a slip-joint formed between them, the bezel being detached and an edge portion broken away and showing the parts of the joint similarly inclined.

Corresponding and like parts are referred to in the following description and indicated in all the views of the drawings by the same reference characters.

The case-center is indicated at 1 and comprises inner rims 2 and 3, the latter being wider than the former in order to engage with the shoulder 4 of band 5 and support same from displacement in one direction. The pendant 6 of the stem projects from the case 1 and is internally threaded to receive nut 7, connected to stem 8 by a bushing-joint. Packing 9 is slipped upon the upper end of stem 8 and is confined between nut 7 and bushing 60 10 and is clamped by crown 11, secured to the upper end of stem 8. Packing 9 insures the formation of a dust-proof joint between stem 8 and adjunctive parts. Band 5 is of a size to snugly fit within case 1 and is provided with 65 outer shoulder 4 for engagement with inner rim 3 and with inner shoulder 12 for engagement with the movement (not shown) to support same in the accustomed way. The band is provided with threaded extensions 13 and 14, the latter projecting beyond inner rim 3 of case 1 to receive cap or back cover 15 and threaded extension 13, adapted to receive bezel 16, the case being confined between bezel 16 and cap 15, the fit between the parts being such as to exclude 70 dust and moisture. Band 5 is provided with an opening to admit of the passage of stem 8 and is likewise notched for the passage of lever 17 of the type of movement adapted to have its hands-setting mechanism thrown into 75 gear by means of a lever or lateral sliding extension.

The front cover 18 is hinged to case 1 in the usual way and when released from the catch-spring is thrown open by lift-spring 19, same 85 being located in the space formed between band 5 and case 1. Catch-spring 20 is similarly located in the space formed between band 5 and case 1, and its active portion is adapted to engage with cover 18 and hold same 90 closed against the action of lift-spring 19 in the manner well understood. It is noticed that both springs 19 and 20 are located exterior to band 5, thereby preventing the formation of any openings in band 5 which would 95 admit dust or moisture.

The cap or back cover 15 protects the movement in the rear, and the cover 18 performs the same office for the front. All the advantages of the usual hunting-case are attained 100

without the expense attendant upon the provision of the inside back cover, which in the present instance is dispensed with. By having the cap or back cover 15 and bezel 16 connected to band 5 by a screw-thread joint a tight joint is insured, and the parts may be readily disconnected by the proper application of force to loosen and admit of unscrewing the parts. The first cost is reduced as to material and labor, and the timepiece is materially lightened and enabled to be of smaller size with a movement of given diameter and thickness.

The construction of case illustrated is principally designed for stem-setting movements; but when the invention is applied to lever-set movements the bezel and band are notched to admit of the lever working between them, as illustrated most clearly in Fig. 9. The crown 11 overlaps shell 6 a sufficient distance to prevent exposing the joint when stem 8 is moved outward to throw the hands-setting mechanism into gear. The case is prevented from movement in one direction with reference to the band by the back 15 and from movement in the opposite direction by bezel 13, said parts 13 and 15 clamping opposite sides of the case and acting jointly therewith and with the band to hold the movement against displacement. To insure correct positioning of band 5 and prevent turning thereof in the case when screwing or unscrewing the back and bezel, pin 23 extends outward from the band and is adapted to enter a notch or depression 24 of the case.

Having thus described the invention, what is claimed as new is—

1. In watchcase construction, the combina-

tion of the case-center having spaced rims extended inward to unequal distances to form 40 openings of varying diameter at opposite sides, a band insertible through the larger opening at one side of the case and having an outer shoulder to engage with the inner side of the rim at the opposite side of the case, and 45 having a reduced end portion passed through and beyond said rim, and a clamp-piece threaded upon the projected end of the band to confine the inner edge portion of the rim between said shoulder and clamp-piece, substantially 50 as set forth.

2. In watchcase construction, the combination of the case-center having spaced rims extended inward to unequal distances to form 55 openings of varying diameter at opposite sides, a band insertible through the larger opening at one side of the case and having an outer shoulder to engage with the inner side of the rim at the opposite side of the case, and having a reduced end portion passed through 60 and beyond said rim and having its opposite end portion exteriorly threaded and extended beyond the side of the case-center having the larger opening, a bezel threaded upon one end of the band and a cap threaded upon the 65 opposite end to clamp the case-center between them, one of said parts also serving to clamp the wider rim of the case-center against the shoulder of the band, substantially as set forth.

In testimony whereof we affix our signatures 70 in presence of two witnesses.

HERMAN H. PATRY. [L. S.]
LOUIS SAMUEL HANSON. [L. S.]
